We claim the ornamental design for a battery receptacle, as shown and described.

DESCRIPTION

FIG. 1 is a bottom perspective view of a battery receptacle, showing our new design;

FIG. 2 is a front view of a right half of a battery receptacle, shown separately for ease of illustration.

FIG. 3 is a rear view thereof;

FIG. 4 is a rear perspective view thereof;

FIG. 5 is a bottom view thereof;

FIG. 6 is a front perspective view perspective of a left half of the battery receptacle, shown separately for ease of illustration;

FIG. 7 is a rear view thereof;

FIG. 8 is a rear perspective view thereof; and,

FIG. 9 is a bottom view thereof.
